UNITED STATES PATENT OFFICE.

ARTHUR HAROLD HOBART, OF HONOLULU, TERRITORY OF HAWAII.

MEANS FOR CEMENTING WELLS.

Application filed December 14, 1926. Serial No. 154,750.

This invention relates to means and method for introducing cementitious material into the shaft of artesian wells for the purpose of sealing them.

5 The object of the invention is to provide means for conserving the water supply of artesian basins by stopping the flow therefrom, through abandoned wells.

In the drilling of deep wells to obtain 10 water supply in certain localities, as example, in the Hawaiian Islands, the wells are projected to varying depths from 250 to 1000 feet, in order to reach the artesian basins which lie from 200 to 900 feet below sea level.

15 These wells, before reaching the fresh or sweet water bearing strata, pass through sand, coral, or other pervious material, which is saturated with salt water from the ocean.

In the work of projecting these wells, metallic casings are inserted into the well bore, and carried to a point below this pervious strata, to shut off such salt water as might find its way into the well through the pervious strata, from the ocean. These casings 25 are left in the completed well to continue to keep the salt water from entering and commingling with the sweet water from the lower basin source.

The water emanating from the pervious 30 strata being salty, soon rusts out the metallic casing, causing either a leakage of salt water into the well, or a leakage of sweet water out through the pervious strata, thus depleting the basin, and lowering the head of flow from the well above sea level.

35 When a well so affected is abandoned on account of its not warranting re-casing, or for other reasons, it is considered good practice to completely seal it off, for the dual 40 purpose of shutting out the incoming salt water from the sea, into the basin, and to stop further depletion of the basin supply by any outward flow through the pervious strata.

In the localities referred to, the head of 45 the flow of artesian wells has dropped approximately fifty per cent in the past fifty years, and partially due to the lowering of the head, there has occurred the creeping in from the ocean salt water into the seaward 50 ends of many of the basins, making the water from wells tapping such basins, too salty to be of value for irrigation or other purposes. I have found that by sealing off from ten to two-hundred feet in the bottom of some of 55 these wells, that I have reduced the salt con-

tent from 10% to 70%, and have completely stopped further depletion of the basins comprising the source of these wells.

Broadly speaking, the preferred embodiment of my invention comprises a tubular 60 container having a detachable bottom adapted to support a charge of cementitious material positioned within said container, and means for detaching the bottom, to release the material from said container, when the 65 container has reached a pre-determined position within the well, and my invention further consists in the formation of, and the depositing at fixed positions within the well, cementitious material capable of resisting the 70 upward flow of water from the source of supply, while the cementitious material is in a plastic condition.

In the process of sealing off sub-surface water, and water from the bottom and intermediate zones in deep wells, it is customary 75 to introduce cement into the well by means of an elongated container, usually called a dump bailer, having a foot valve which is opened when the bailer comes in contact with 80 the bottom of the well, supposedly discharging the cement at this point.

Where the bailer encounters soft material in the bottom of the well, the dart of the bailer valve will sink in, and fail to 85 function, and the bailer fails of discharge. Furthermore, the foot valves in common use are so constructed that even when opened, they constrict the discharge orifice of the bailer to such an extent that the cementitious 90 material positioned within the bailer often fails to be exuded. This non-action of the bailer cannot be ascertained until the bailer is withdrawn from the well, preparatory to again loading for another charge. 95

I overcome these difficulties by my improved bailer, in providing at the bottom thereof, an unrestricted discharge opening, and means for mechanically evacuating the cementitious material within the bailer. 100

It has also been found that in the operation of depositing cement in deep wells, especially where the head or volume of flow of the water therefrom, is of considerable magnitude, that the ordinary cementitious material having 105 about the specific gravity of Portland cement, would not resist this flow, but would be buoyed up and carried out of the well with the water. I overcome this difficulty by increasing the specific gravity of the cementi- 110

tious material I use, by commingling therewith pieces of iron, such as chips, borings, boiler punchings, etc., as well as scrap lead and other heavy metals.

5 I may make my first deposits of cementitious compound, rich in iron ingredients, and I may add other ingredients which will materially hasten the oxidation of the iron ingredients from the effects of salt water thereon, into a solid mass with the casing, making a permanent immovable plug, thereby reducing the flow of water, which will facilitate the maintenance in position while setting, the subsequently positioned cement mixture on 10 top thereof.

As the point desired at which to place the water seal in deep wells, is generally at an intermediate point, I have found it advantageous to build up a foundation from the 20 bottom to such point by employing for this purpose, a plurality of pre-cast concrete cylinders, formed with or without reinforcements, as shown in Fig. 4 of the drawings, which are lowered into the well by means well 25 known in the art, until the intermediate point is reached at which the water seal is to be placed.

I accomplish the effective sealing of deep wells by a method and apparatus herein described and illustrated in the accompanying drawings forming a part of these specifications.

In the drawings:

Fig. 1 is a side elevation and partial section 30 of my improved dump bailer charged with cementitious material ready for use in a well.

Fig. 2 is a similar view to Fig. 1, showing the position assumed by the component parts 40 of the bailer upon reaching the bottom of the well.

Fig. 3 is a side elevation with parts broken away, of the bailer after the charge of cementitious material has been evacuated.

45 Fig. 4 is a side elevation of pre-cast concrete cylinders positioned in the bottom of the well upon which is to be deposited cementitious material.

Fig. 5 is an enlarged detailed view of the 50 latch mechanism.

Fig. 6 is a view taken on the line 6—6 shown in Fig. 5.

In the drawings, 1 indicates the tubular container for holding the cementitious material, 2 is the closure member for the tubular container formed with the shoulder 3, adapted to form a seal with the annular rim 4 of the bottom of the container 1.

60 Mounted on the upper end of the tubular container 1, and extending upwardly therefrom, are the companion supporting bars 5 and 5'. Positioned on each side of the supporting bars 5 and 5', at their upper ends are transverse companion bars 6 and 6' (6' not shown). A similar pair of transverse

companion bars 7 and 7' (7' not shown) are positioned on the supporting bars 5 and 5' a short distance below the bars 6 and 6'.

Intermediate of the bars 6 and 6' and bars 7 and 7', there is formed a rectangular aperture within which is positioned the slidable member 10, formed rectangular in cross section to conform to the aperture in which it slides. The slidable bar 10 is adapted for vertical movement with respect to the container 1, but is held against a rotative movement therein.

70 The slidable member 10 has formed in its upper end the eye 11, and in its lower end the eye 12. Located near the upper end of the slidable member 10, is a spring actuated pawl 8 positioned within the recess 18 formed in the body of the member 10. The pawl 8 pivoted on the rivet 19, is adapted to be held in extended position by the compression spring 20. To guard against the pawl 8, or the spring 20 becoming inoperative by clogging of cementitious material therewith, I have provided the apertures 21 and 21' in 80 the bottom of the recess 18, for the free admission of water therethrough to clear the recess 18 of any of the cementitious material that may become lodged therein.

85 Connected to the eye 12 in the lower terminal of the slidable member 10, is the upper end of the chain 13. The lower end of the chain 13 is shackled to the eye bolt 14 projecting from the upper end of the closure member 2.

90 The closure member 2 comprises the valve 100 seat 3, and the tubular extension 9, which is filled with lead or other heavy material to provide a suitable anchor for the purposes hereinafter described.

95 The upper terminal of the slidable member 10 is adapted to be connected by the eye 11, to the lowering means (not shown) by which the apparatus is lowered into the well, and usually comprises a portion of the string 105 of well tools applied in a manner well known 110 in the art.

To those skilled in the art, it will be obvious that as the container and its component parts, are suspended by the eye 11, of the member 10, a strain will be applied to the chain 13 which will hold the bottom member 2, in position to form a closure with the rim 4 of the container 1, forming an effective seal therewith. With the container 1, thus suspended, it is adapted to hold a charge of cementitious material placed therein, and to retain it during the operation of lowering the apparatus to the point in the well desired. When this point has been reached, either at the natural bottom of the well, or at an artificial bottom built up by the use of pre-cast concrete cylinders as shown in Fig. 4, the lower closure member 2, coming in contact therewith, arrests the downward movement of the container 1. Such contact how- 125 130

ever, does not abruptly arrest the downward movement of the slideable member 10 which is free to continue its downward movement, actuated by the pressure thereon, of the well tools being lowered, until the eye 11 has reached a position contiguous with the companion transverse bars 6 and 6'. When this position has been reached by the sliding member 10, there will have occurred a slackening of the links of the chain 13, with a depositing of such slack links on top of the cementitious material as shown in Fig. 2, and the pawl 8, will have reached a position below the transverse bars 6 and 6' and assumed an extended position to engage the transverse bars 6 and 6' in its subsequent upward movement.

The apparatus is now in a position for discharging the cementitious material within the container. This discharge is accomplished by the upward movement of the well tools which carry with them the slideable member 10. In the upward movement of the member 10, the pawl 8 being extended, engages the transverse bar 6, and through such engagement, the container 1 is lifted and carried upward with the movement of the bar member 10, thereby severing the closure between the annular rim 4 of the container 1 and the valve seat 3 of the closure member 2, separating the container 1 from the closure member 2, to the extent of the slack previously formed in the chain 13, thereby allowing a free discharge of the cementitious material from the container 1.

To facilitate the discharge and to assure a complete functioning thereof, a reciprocal movement is given to the hoisting means which in turn causes the chain 13, secured at its lower end to the closure member 2 acting as an anchor, to be reciprocated through any cementitious material in its path, and to accelerate an evacuation thereof from the container 1.

As further assurances of a complete cleaning out of the interior of the container 1, the apparatus is lifted to a zone above the cementitious deposit, and again given a reciprocating movement, forcing the water standing in the well, through which the container is reciprocated to act on the sides thereof to remove any particles adhering thereto.

The apparatus is then hoisted to the surface of the ground and the process is repeated until a sufficient amount of cementitious material has been deposited within the well to insure a complete sealing thereof.

With the foregoing description I have referred to a method and apparatus for cementing wells, and while I have described the preferred embodiment of my invention, I desire it to be understood that I do not limit myself to the specific details shown, as other methods and means may be employed to carry out my invention, without departing from the spirit thereof.

What I do claim and desire to secure by Letters Patent is:

In a device for cementing wells, comprising a supporting rod, a cylindrical anchor member suspended from said rod by loose jointed connections and adapted to be positioned on the bottom of the well, a tubular member surrounding said rod adapted to contain cementitious material and supported on said anchor member, a bail member attached to said tubular member recessed to engage the rod therein, a latch pawl pivoted in said rod adapted to pass the bail member on a downward movement of the rod and to engage the bail member in its upward movement whereby the tubular member is lifted and spaced apart from the anchor member in the withdrawal movement of the apparatus from the well.

In testimony whereof I have affixed my signature.

ARTHUR HAROLD HOBART.
